US00D988303S

(12) **United States Design Patent** (10) **Patent No.:** **US D988,303 S**
(45) **Date of Patent:** **** Jun. 6, 2023**

(54) **PORTABLE INPUT/OUTPUT DEVICE**

(71) Applicant: **Amazon Technologies, Inc.**, Seattle, WA (US)

(72) Inventors: **Emmanuel J M Laffon de Mazieres**, Burlingame, CA (US); **Giles David Mattheus McWilliam**, San Francisco, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/828,188**

(22) Filed: **Feb. 24, 2022**

Related U.S. Application Data

(62) Division of application No. 29/747,556, filed on Aug. 24, 2020, now Pat. No. Des. 949,133, which is a division of application No. 29/625,802, filed on Nov. 13, 2017, now Pat. No. Des. 900,795.

CLAIM

The ornamental design for a portable input/output device, as shown and described.

DESCRIPTION

FIG. 1 is a top, front, right-side perspective view of a portable input/output device;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The dashed broken lines depict portions of the portable input/output device that form no part of the claimed design.

1 Claim, 7 Drawing Sheets
